UNITED STATES PATENT OFFICE.

RICHARD M. BECKER, OF NEW YORK, N. Y., ASSIGNOR TO JOHN T. UNDERWOOD, OF BROOKLYN, NEW YORK.

TYPE-WRITING MACHINE.

1,150,164.

Specification of Letters Patent. Patented Aug. 17, 1915.

Application filed February 12, 1913. Serial No. 747,839.

To all whom it may concern:

Be it known that I, RICHARD M. BECKER, a citizen of the United States, residing in Brooklyn, in the county of Kings, city and State of New York, have invented certain new and useful Improvements in Type-Writing Machines, of which the following is a specification.

My invention relates to typewriting machines, and for convenience is described as applied to an Underwood typewriter, of the front strike type, in which the work-sheet is inserted from the rear over a paper table which guides the work-sheet down beneath the platen, so that the sheet will rise in front of the platen to the printing point. The platen is usually provided with pressure-rolls which bear against its underside, and which may be cast off from the platen by means of a hand-lever conveniently placed at one end of the typewriter carriage.

My invention is directed particularly to the feed or pressure-rolls. In the Underwood typewriter there are front and rear sets of feed-rolls.

One feature of the invention is to furnish means whereby pressure-rolls may be utilized in squaring a work-sheet which is inserted into the machine. For this purpose one set of said rolls may be arranged so they can be separately cast off from the platen while the other set of said rolls still remains in contact with the platen. The paper or work-sheet may then be centered against the rolls which still bear against the platen, and then the work-sheet is gripped in place by restoring the other set of rolls to normal position against the platen. This affords means of gripping the paper in place while it is still squared against the rolls which have been left against the platen. Thus there is no possibility of the work-sheet becoming displaced during the operation of moving a member to hold it positively against the platen.

Other features and advantages will hereinafter appear.

In the accompanying drawings Figure 1 is a sectional side view of the carriage of an Underwood typewriting machine taken on the line 1—1 of Fig. 6. Fig. 2 is a similar section taken on the line 2—2 of Fig. 6, and also showing the lever operated to throw off the rear pressure rolls. Fig. 3 is a fragmentary section on the line 3—3 of Fig. 6. Fig.

4 is a fragmentary view perspective of a carriage showing the principal parts necessary to the understanding of my invention. Fig. 5 is a detail showing the means for casting off the rear pressure-rolls. Fig. 6 is a top plan view of the carriage partly diagrammatical, and also shows a modified mounting for the rock shaft which is operated to throw off the rear feed rolls.

The carriage of an Underwood typewriting machine comprises end-plates 1 and 2 connected by a paper table 3 at the rear of the carriage, and a tie-rod 4, near the bottom of the carriage. In the ends 1 and 2 is journaled a platen 5 fast on an axle 6, and against the bottom of said platen are pressed feed or pressure-rolls 7 and 8. The front rolls 7 are carried on a shaft 8^a, which is journaled in hooks 9 of arms 10, said arms being pivoted on the tie-rod 4, and said arms being extended beyond said tie-rod (as seen in full lines in Fig. 4 and in dotted lines in Figs. 1 and 3) so that a turned-up lip 11 on each extension furnishes a bearing for a spring 12, which constantly tends to press front roll 7 against the platen. There is preferably one of said springs at each end of the platen, and said springs may have their tension adjusted by a screw 13 in each lip 11, and said springs may bear against said screws by means of cups not shown herein, and the screws may be locked in place in any usual or approved manner. Said springs bear at their opposite ends against brackets 14 fast on the tie-rod 4.

The rear pressure-rolls 8 are carried on a shaft 15, which like the front shaft is journaled in hooks 16, said hooks being at the rear ends of arms 17, which arms include lips 18 overlying springs 19, which springs like the springs 12 bear against brackets fast on the tie-rod 4 and hold the rolls 8 against the platen. Said rolls may be cast off in the usual manner by a handle 20 at one end of the carriage. Said handle, by means of a link 21 extending downward from the extension of said handle, swings a rock-shaft 22 pivoted in brackets 23 fast on said tie-rod, and causes said shaft to cast the rolls 7 and 8 off from the platen. To do this the shaft 22 is rotated by means of a crank 23^a thereon, which the link 21 draws on; and the rotation of said shaft 22 turns a flat face 24 from the position seen in Fig. 1 to the position seen in Fig. 2. In so turning,

the edge of said flat portion cams upwardly an overlying arm 25 which is pivoted on an arm 34 fast on the tie-rod 4, so that the farther end 26 of said arm 25 overlying the 5 shaft 15 of the rear pressure-rolls, forces said shaft and rolls downward away from the platen. The end of said arm 25 nearest the rock-shaft 24 underlies a pin 27 fast on the arms 10 on which the front pressure- 10 rolls are journaled, so that when said arm 25 is raised, it moves the front rolls 7 away from the platen against the tension of their springs 12.

When the rolls are bearing against the 15 platen the rear pressure-rolls 8 may be cast off from said platen separately, and then a paper passed from the rear of the typewriter over the paper table 3 may be pushed forwardly under the platen past said rear 20 rolls until it strikes the front pressure-rolls 7. In this way said front pressure-rolls may be utilized in squaring the work-sheet in the machine. The paper table 3 is extended forward beneath the platen to or 25 beyond the front rolls 7, and is spaced from the platen to form a passageway through which the work-sheets are guided in bringing the leading edge up to the gage rolls 7. For thus moving away said rear rolls there 30 is provided a finger lever 28 fast on a shaft 29 journaled in the arms 25. When the finger-piece 28 is moved rearwardly, it rocks the shaft 29 so that arms 30 fast thereon bear down on the shaft 15, and press the 35 rear rolls 8 downward clear of the platen, so that a work-sheet may be easily pushed past them. The arms 25 in which the shaft 29 is journaled are kept alined by turned-up extensions 31 lying outside of the tie-rod 4 while the main body of the arm 25 40 lies between the arms 10 and a collar 32 fast on the tie-rod. Each arm 25 also comprises an extension 33 above the floating-shaft 29, which extension is pivoted to the arm 34 ex- 45 tending from the collar 32 on the tie-rod 4. The arrangement of said pivotal mounting of the arm 25 is best seen in Fig. 5 where it is shown on an enlarged scale. From said Fig. 5 it will be clearly seen that each 50 method of casting off the rear feed-rolls is entirely independent of the other method, so that the two sets of casting off mechanism can in no wise interfere with each other.

A spring 35 encircling the shaft 29 holds 55 the finger-piece 28 in its normal position even when the pressure-rolls are cast off by the handle 20. One end of said spring is anchored by coils which encircle the rock-shaft 22, while the other end of said spring nor- 60 mally holds the finger-piece 28 in its for-ward position. The handle 28 is preferably at the left-hand end of the carriage where the left-hand may easily operate it while the right-hand is adjusting the work-sheets 65 in the carriage.

It will be observed that the finger-piece or handle 28 is placed not far from the paper table 3, and to cast off the rolls 8 it is moved from the position seen in Fig. 1, which is considerably forward of said table 70 to the position seen in Fig. 2, where it lies against the table. Thus it is convenient for the hand or wrist of the operator in moving a work-sheet, to bear down against said handle 28 and keep the roll 8 released while the work-sheet is being adjusted. Since there is no detent or other device holding the handle 28 in its releasing position, the mere lifting of a hand of the operator will cause the pressure-roll 8 to grip the work-sheet. In other words, both hands of the operator can be used in adjusting a sheath of sheets at one time, while the back or wrist of the left-hand of the operator is holding the pressure-roll 8 released, and the 80 mere lifting of the hand of the operator will permit said roll to bind and hold the sheets wherever adjusted.

The shaft 29 instead of being carried as a floating shaft in the arms 25 may, if de- 90 sired, be journaled in the platen frame, as shown in Fig. 6.

Variations may be resorted to within the scope of the invention, and portions of the improvements may be used without others. 95

Having thus described my invention, I claim:

1. In a front-strike typewriting machine, the combination with a platen, of front and rear pressure rolls beneath said platen, a 100 paper table behind said platen, means for holding said rolls against the platen, means for casting off the rear pressure rolls separately from the front pressure rolls, the front rolls being retained against the platen 105 and forming a gage for the leading edge of a work-sheet, said rear pressure rolls when cast off leaving an unobstructed pas- 110 sageway for advancing the work-sheet from the paper table between the platen and rear rolls, to the front rolls, a key, and means operated by the key for simultaneously casting off all of said rolls.

2. In a front-strike typewriting machine, the combination with a platen and front and rear sets of pressure rolls for said platen, of means for independently holding the front and rear rolls with a yielding pressure against the platen, a paper table behind said platen, a key, means operated thereby to simultaneously overcome the holding power of both sets of rolls for releasing said sets simultaneously from said platen, and means for casting off the rear rolls separately from the front rolls. 115

3. In a front-strike typewriting machine, the combination with a platen, of front and rear sets of pressure rolls beneath the platen, springs holding each set of rolls against the platen independently of the 120 125 130

other set, one set of rollers forming a gage for a work-sheet, a finger-piece at the left-hand end of said platen for casting off the other set of rolls while the first set is retained against the platen and leaving a free passageway for the leading end of the work-sheet to be inserted between the cast off rolls and the platen and moved along the platen to the gage rolls, and a device for 10 simultaneously casting off all of the pressure rolls.

4. In a front-strike typewriting machine, the combination with a platen and front and rear pressure rolls beneath said platen, 15 of means for normally holding said rolls against the platen, a paper table across which a work-sheet is fed past said rear rolls to said front rolls, a key, means operated by the key for simultaneously casting off both sets of said rolls, and means for casting off the rear rolls without casting off the front rolls.

5. In a typewriting machine, the combination with a rotatable platen, of front and 25 rear pressure-rolls bearing against said platen, springs for independently pressing said rolls against said platen, an arm for casting off said rolls simultaneously from said platen, and an independently movable 30 arm for casting off one set of said rolls independently of the other set.

6. In a typewriting machine, the combination with a platen and front and rear pressure-rolls running thereon, of a spring 35 for each of said rolls normally holding them against the platen, an arm overlying one set of said rolls, means for moving said arm so as to move said rolls and the other rolls simultaneously from said platen, and a second arm overlying said first set of rolls for 40 moving said rolls separately from said platen.

7. The combination with a platen, of a roll normally pressed against the platen 45 and forming a gage for the leading end of a work-sheet, another roll past which the work-sheet is carried in being inserted in

the typewriter, said second roll normally bearing against the platen, means for casting off the platen without disturbing said first roll, a key, and a device 50 operated thereby for simultaneously casting off both of said rolls.

8. In a front-strike typewriting machine, the combination with a rotary platen, of front and rear pressure rolls, means for holding said rolls with a yielding pressure 55 against the platen and permitting either roll to be moved from the platen independently of the other roll, means for throwing off the rear roll while the front roll remains against the platen to form a gage for the leading edge of a work-sheet, a paper table at the rear of the platen and extending forwardly beneath the platen, said extension 60 being spaced from the platen to form a passageway through which the leading edge of the work-sheet may be freely moved while the platen is at rest and the rear roll moved away from the platen, to bring the edge of 65 the work-sheet against said gage roll, a key, and means operated thereby for simultaneously throwing both the front and rear pressure rolls off the platen.

9. In a typewriting machine, the combination with a platen and front and rear pressure rolls therefor, of means for holding each of said rolls against the platen with a spring pressure, each of said rolls movable away from the platen independently of the other, said front roll forming a gage for the leading edge of a work-sheet, 75 a paper table extended forward to said front roll and forming with the platen a passageway through which a work-sheet 80 may be freely moved, means for casting off the rear pressure roll independently of the front roll, and a key actuated device to simultaneously cast off both said rolls by the 85 actuation of the key.
